SICKLE GUARD AND MOUNTING

Otto R. Schoenrock, Oak Park, Ill., assignor to
 J. I. Case Company, Racine, Wis., a corporation
 of Wisconsin

Application July 8, 1947, Serial No. 759,540

6 Claims. (Cl. 56—307)

1

My invention relates to sickle guards and mountings.

One of the objects of my invention is to simplify the sickle guard and its mounting and to eliminate parts where possible.

A further object is to provide a lateral bracing for the guards.

Further objects and advantages of the invention will be apparent from the description and claims.

In the drawings in which an embodiment of my invention is shown,

Figure 1 is a plan view showing a cutter bar rail and sickle guard mounted thereon;

Fig. 2 is a section on the line 2—2 of Fig. 1;

Fig. 3 is a perspective view of the sickle guards and mounting, and

Fig. 4 is a section on the line 4—4 of Fig. 2.

Referring to the drawings in detail, the sickle guard and mounting shown comprises a cutter bar rail 1, a plurality of spaced bracket-like tongues 2 secured thereto and extending forwardly therefrom, a wear plate 3 for engaging the rear edge of the sickle bar 4 and supporting it against rearward thrust, a plurality of sickle guard fingers 5, one secured to each of the tongues 2, an apron 6 extending parallel to the rail 1 above the tongues 2, a second apron 7 extending parallel to the rail 1 below the tongues, a plurality of ledger plates 8, one secured to each finger 5 by means of rivets 8a, a plurality of hold-down clips 9 for holding the sickle sections 10 against the ledger plates 8, and bolts 11 extending through the aprons 6 and 7, clips 9, wear plate 3, guard fingers 5 and tongues 2 for securing them together. The sickle sections 10 are secured to the sickle bar 4 by means of rivets 11a.

Each guard finger 5 comprises an integral metal stamping having an inverted channel portion comprising an upper elongated medial web portion 12 and two elongated spaced flanges 13 extending downwardly from the opposite sides of the upper web portion, respectively. These flanges are spaced far enough apart to enable the insertion and withdrawal of a forming tool by movement transversely with respect to the medial portion.

The medial portion 12 comprises a finger tip portion 14, a flat ledger plate supporting portion 15 in the rear of the tip portion, a depressed sickle bar clearance portion 16 in the rear of the ledger plate supporting portion, and a flat attaching portion 17 in the rear of the clearance portion 16.

The front end of the tongue 2 lies within the channel portion underneath the attaching por-

2

tion 17 and the clearance portion 16. The side edges of the tongue lie against the flanges 13 to support the guard finger 5 laterally and hold it in alignment. The tongues may be secured to the horizontal flange 18 of the cutter bar rail by welding. These tongues are doubled over at the front end at 19 for the sake of strength and rigidity.

A pressed sheet metal shield or guard 20 may be secured on the upper side of the tip portion 14 by welding or in any suitable manner. The rear end of this shield or guard overlies the sickle sections and serves to support the stalks against the shearing action of the sickle sections.

15 The rear edge of the upper apron 6 is bent over at 21 to provide a double thickness for engagement with the upright leg of the angle bar forming the cutter bar rail 1 to provide resistance to downward forces acting on the guard fingers 5. 20 The lower apron is secured at its rear edge to any suitable support and serves to resist upward forces acting on the guard fingers. The hold-down clips 9 serve to hold the sickle sections in proper relation with respect to the ledger plates. The shield 20 may be provided with an embossment 22 to provide a pocket into which the front tip of the ledger plate 8 is inserted to hold it in position and alignment.

30 Having thus described my invention what I claim and desire to secure by Letters Patent is:

1. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a first apron extending parallel to said rail above said tongues, a second apron 35 extending parallel to said rail below said tongues, a plurality of ledger plates, one secured to each finger, a plurality of hold-down clips for holding the sickle sections against the ledger plates and means extending through said aprons, clips, wear plate, guard fingers, and tongues for securing them together, each guard finger comprising an integral stamping having an inverted channel portion comprising an upper elongated medial web portion and two elongated spaced flanges 40 extending downwardly from the opposite sides of said upper web portion, respectively, spaced far enough apart to enable the insertion and withdrawal of a forming tool by movement transversely with respect to said medial portion, said 45 medial portion comprising a finger tip portion, a

flat ledger plate supporting portion in the rear of said tip portion, a depressed sickle bar clearance portion in the rear of said ledger plate supporting portion, and a flat attaching portion in the rear of said clearance portion, the front end of each tongue lying within the channel portion underneath the attaching portion and the clearance portion, engaging these portions.

2. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a plurality of ledger plates, one secured to each finger, a plurality of hold-down clips for holding the sickle sections against the ledger plates and means for securing together said clips, wear plate, guard fingers, and tongues, each guard finger comprising an integral metal stamping having an inverted channel portion comprising an upper elongated medial web portion and two elongated spaced flanges extending downwardly from the opposite sides of said upper web portion, respectively, spaced far enough apart to enable the insertion and withdrawal of a forming tool by movement transversely with respect to said medial portion, said medial portion comprising a finger tip portion, a flat ledger plate supporting portion in the rear of said tip portion, a depressed sickle bar clearance portion in the rear of said ledger plate supporting portion, and a flat attaching portion in the rear of said clearance portion; the front end of each tongue lying within the channel portion underneath the attaching portion and the clearance portion.

3. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a plurality of ledger plates, one secured to each finger, and means for securing together said wear plate, guard fingers, and tongues, each guard finger comprising an integral metal stamping having an inverted channel portion comprising an upper elongated medial web portion and two elongated spaced flanges extending downwardly from the opposite sides of said upper web portion, respectively, spaced far enough apart to enable the insertion and withdrawal of a forming tool by movement transversely with respect to said medial portion, said medial portion comprising a finger tip portion, a flat ledger plate supporting portion in the rear of said tip portion, a depressed sickle bar clearance portion in the rear of said ledger plate supporting portion, and a flat attaching portion in the rear of said clearance portion, the front end of each tongue lying within the channel portion underneath the attaching portion and the clearance portion.

4. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a plurality of ledger plates, one secured to each finger, holding the sickle sections against the ledger plates and means for securing together said wear plate, guard fingers, and tongues, each guard finger comprising an

integral metal stamping having an inverted channel portion comprising an upper elongated medial web portion and two elongated spaced flanges extending downwardly from the opposite sides of said upper web portion, respectively, spaced far enough apart to enable the insertion and withdrawal of a forming tool by movement transversely with respect to said medial portion, said medial portion comprising a finger tip portion, a flat ledger plate supporting portion in the rear of said tip portion, a depressed sickle bar clearance portion in the rear of said ledger plate supporting portion, and a flat attaching portion in the rear of said clearance portion, the front end of each tongue lying within the channel portion underneath the attaching portion and the clearance portion, engaging these portions.

5. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a plurality of ledger plates, one secured to each finger, and means for securing together said wear plate, guard fingers, and tongues, each guard finger comprising an integral metal stamping having an inverted channel portion comprising an upper elongated medial web portion and two elongated spaced flanges extending downwardly from the opposite sides of said upper web portion, respectively, spaced far enough apart to enable the insertion and withdrawal of a forming tool by movement transversely with respect to said medial portion, said medial portion comprising a finger tip portion, a flat ledger plate supporting portion in the rear of said tip portion, a depressed sickle bar clearance portion in the rear of said ledger plate supporting portion, and a flat attaching portion in the rear of said clearance portion; the front end of each tongue comprising a metal strap, the front end of which is doubled over and lies within the channel portion underneath the attaching portion.

6. A sickle guard and mounting construction comprising a cutter bar rail, a sickle bar, a plurality of spaced bracket tongues secured thereto and extending forwardly therefrom, a wear plate for engaging the rear edge of the sickle bar, a plurality of sickle guard fingers, one secured to each of said tongues, a plurality of ledger plates, one secured to each finger, and means for securing together said wear plate, guard fingers, and tongues, each guard finger comprising an integral metal stamping having an inverted channel portion comprising an upper elongated medial web portion and two elongated spaced flanges extending downwardly from the opposite sides of said upper web portion, respectively, spaced far enough apart to enable the insertion and withdrawal of a forming tool by movement transversely with respect to said medial portion, said medial portion comprising a finger tip portion, a flat ledger plate supporting portion in the rear of said tip portion, a depressed sickle bar clearance portion in the rear of said ledger plate supporting portion, and a flat attaching portion in the rear of said clearance portion, the front end of each tongue lying within the channel portion underneath the attaching portion.
